DESIGN FOR A TEXTILE FABRIC

Paul Reiman, New York, N. Y.

Application January 6, 1937, Serial No. 66,921

Term of patent 3½ years

To all whom it may concern:

Be it known that I, Paul Reiman, a citizen of the Republic of Germany, residing in the city of New York, county of New York, and State of New York, have invented a new, original, and ornamental Design for a Textile Fabric, of which the following is a specification, reference being had to the accompanying drawing, forming part thereof.

The figure is a plan view of a textile fabric showing my new design.

The dot and dash lines on the drawing show the design unit, which unit is repeated in staggered succession, as indicated by the angles A and A'.

I claim:

The ornamental design for a textile fabric as shown and described.

PAUL REIMAN.
